(57) **CLAIM**

The ornamental design for a squeezing device for collapsible flexible tubes, as shown and described.

DESCRIPTION

FIG. 1 is a front elevation view of a squeezing device for collapsible flexible tubes showing my new design, the opposite side being a mirror image of the shown;

FIG. 2 is a bottom plan view thereof;

FIG. 3 is a top plan view thereof;

FIG. 4 is an isometric view thereof; and,

FIG. 5 is a right elevation view thereof, the opposite side being a mirror image of the shown.
